EX
OR D 876

Des. 876

Joseph Bernhard, of Philadelphia, Pa.

Assignor to

J. Bernhard, J. Wendermyer & Louis Ganz, of Philadelphia, Pa.

Letters Patent No. 876. Dated Mar. 24. 1837.

The Schedule referred to in these Letters Patent and making part of the same.

To all whom it may concern:

Be it known that I, Joseph Bernhard, of the City of Philadelphia and State of Pennsylvania have invented a new and original design for self cooling draught apparatus for soda water, and I do hereby declare, that the following is a full, clear and exact description of the same, referenced briefly had to the accompanying drawings, making part of this specification, and in which

Fig. 1, is an elevation,

Fig. 2, a vertical section of the draught apparatus.

The urn shaped portion A, is provided with the lining a, and the cover B, is lined with the disc b, whereby they are made better nonconductors: C, is the pipe, which passing from the inside of the urn through its bottom, extends to the fountain from which the soda water is to be drawn. It is provided with a collar c, forming a watertight joint with the flange d, of pipe e, which pipe passes through the bottom of the urn and against the lower end of which is screwed the tightening nut f.

Above the collar c, on the pipe C, is attached the lower termination of a pipe D, which is coiled upwards in a spiral manner, following the shape of the lining a, until near the top of the same, where its end is turned towards the centre and terminates in the upper head of an upright cylindrical nut F, which is illustrated by the solid end of hitherto

C. From this vessel branch off the two draw pipes C, C, which enter the vessel near its top and inside extend nearly to the bottom.

The ornamental spouts H, H, configured into the shape of swans heads, are cast hollow, to the root of the bill, through which are drilled small holes n, n, and from which pipes q, q, lead through the side of the urn and connect with the pipes a, a, by means of couplings I, I, K, K, are compression cocks of the ordinary construction, by which the flow of the soda water is effected or checked as required. The upper head of the cylinder F, is provided with a small valve I, by means of which any air can be let off, that might have collected in the cylinder or spiral pipe before its attachment to the fountain.

It will be easily seen, that when the urn is filled with ice, the soda water must before reaching the cylinder F, be entirely cooled, as it has previously to go through the entire spiral pipe. The cock M, serves to let off the water from the inside of urn A, which accumulates as the ice melts away. The cover B, is provided with an ornamental rim h, which matches with another rim i, around the body of the urn A. Three dolphins, resting with their heads on the rim of a small vase at the top of cover B, and supporting a ball (as shown in the drawing) form an ornamental and convenient handle.

Having thus described the nature of my invention, I wish it to be understood, that I do not claim any of the mechanical arrangements of the apparatus, (although I have described them in the specification), but what I claim and desire to secure by letters patent, is the design and configuration of the parts A, B, H, H, of the self cooling draught apparatus as herein shown and described.
